UNITED STATES PATENT OFFICE

116,817

DESIGN FOR DRAWERS OR SIMILAR ARTICLE

Ida Dietz, Brooklyn, N. Y.

Application February 15, 1939, Serial No. 83,003

Term of patent 14 years

To all whom it may concern:

Be it known that I, Ida Dietz, a citizen of the United States, and resident of Brooklyn, in the county of Kings, in the State of New York, have invented a new, original, and ornamental Design for Drawers or Similar Article, of which the following is a specification, reference being had to the accompanying drawing, forming a part thereof.

Figure 1 is a front view of drawers or similar article, showing my design, and Figure 2 is a side view of the same, showing my design. The back of the drawers is conventional. The characteristic feature of my design resides in the combination on the drawers disclosed of the button trimmed pockets arranged as shown.

I claim:

The ornamental design for drawers or similar article, as shown and described.

IDA DIETZ.
